SPECIFICATION forming part of Design No. 22,615, dated July 18, 1893.

Application filed June 1, 1893. Serial No. 476,297. Term of patent 3½ years.

To all whom it may concern:

Be it known that I, JOHN H. ANDERSON, a citizen of the United States, residing at Paterson, in the county of Passaic and State of New Jersey, have invented and produced a new and original Design for Kerchiefs; and I do declare the following to be a full, clear, and exact description of the same, reference being had to the accompanying drawing, forming a part thereof.

The essential features of my design consist of a handkerchief having a fanciful border, a fringe border along the edge and within said fanciful border the representation of the Woman's Building of the Columbian Exposition at Chicago, and a scroll at one end of the building, as shown in the accompanying drawing forming a part of this specification.

—A— is the building; —B— is a panel bearing the representation of the building; —C— the scroll; —D— a fanciful border and —E— a fringe border for the kerchief.

With this description what I claim is—

The design for kerchiefs, substantially as herein shown and described.

In testimony whereof I affix my signature in presence of two witnesses.

JOHN H. ANDERSON.
